US00D770325S

(12) **United States Design Patent** (10) **Patent No.:** **US D770,325 S**
(45) **Date of Patent:** **** Nov. 1, 2016**

(54) **PENGUIN FIGURINE**

(71) Applicant: **Tencent Technology (Shenzhen) Company Limited**, Shenzhen, Guangdong (CN)

(72) Inventor: **Xiao Hu**, Guangdong (CN)

(73) Assignee: **Tencent Technology (Shenzhen) Company Limited** (CN)

(**) Term: **14 Years**

(21) Appl. No.: **29/477,639**

(22) Filed: **Dec. 24, 2013**

(51) **LOC (10) Cl.** **11-02**

(52) **U.S. Cl.**

USPC **D11/158**

(58) **Field of Classification Search**
